[57] ABSTRACT

An apparatus system, including a programmed general purpose computer, for sensing the closed or opened state of large numbers of discrete points. The sensed points are placed in groups. System operation is initiated under control of the computer. Thereafter, the system interrogates each group of sensed points sequentially. During each group interrogation, all sensed points are first examined in parallel. If all sensed points are in a normal state, the following group is then interrogated. If any are in an off-normal state, each point in the group is scanned individually. An interrupt to the computer is then generated after which the computer takes action pursuant to stored error routines.

MONITOR SYSTEM FOR SENSING DISCRETE POINTS

This is a continuation of application Ser. No. 105,560, filed Jan. 11, 1971.

CROSS-REFERENCE TO RELATED APPLICATIONS

This application contains disclosure in common with or related to that of two other applications filed on the same date herewith: Digital Animation Apparatus and Methods, Ser. No. 105,597, filed Jan. 11, 1971, now U.S. Pat. No. 3,767,901; and, Method of Indexing and Arranging Data in Storage, Ser. No. 101,455, filed Jan. 11, 1971, now abandoned. The additional disclosure of those applications is relied upon as disclosure herein.

BACKGROUND OF THE INVENTION

This invention relates to discrete monitor systems, and, more particularly, to systems for sensing the on or off state of large numbers of discrete devices such as switches. A programmed general purpose digital computer is used as part of the system to monitor, on a repetitive and continuous basis, any aspect of any other system or process which can be expressed in terms of on-off devices. An example of the type of system which may be monitored by the system disclosed and claimed herein is set forth in the co-pending application described above, entitled Digital Animation Apparatus and Methods. When an off-normal discrete condition is sensed, the computer is notified and controls a response determined by previously stored subroutines.

It is common for many controlled systems and processes to include numerous devices which must operate at certain times or in a particular way. Quite often, it is necessary to continually monitor such devices to insure proper operation of the system as a whole. Generally, operation of many such system or process aspects may be expressed in terms of discrete or on-off devices. Obviously, it would be a very considerable, if not impossible, problem to manually monitor operation of a system in which the monitored aspects would total dozens or even thousands. This invention provides means and methods of monitoring such systems on a continuous and repetitive basis.

SUMMARY OF THE INVENTION

In this invention, the state of many thousands of discrete points may be continuously and repetitively monitored. The points to be monitored are arranged in groups. All points in a group are first scanned in parallel. If an off-normal status of one or more points is sensed, each point is then scanned individually. The computer is notified of an off-normal status and the identity of the point or points involved. The computer then responds with a controlled output determined by previously stored subroutines. The computer is not involved in the operation of the scanning unless an off-normal condition is sensed. This results in a saving of computer time over prior art discrete monitor systems.

BRIEF DESCRIPTION OF THE DRAWINGS

FIG. 1 is a block diagram of the Monitor System.

FIG. 2 is a block diagram of the Monitor Scanner of the Monitor System.

FIG. 3 is a block diagram of the Overhead portion of the Discrete Scanning Unit of the Monitor System.

FIG. 4 is a schematic diagram of a Scanning Circuit of the Monitor System.

BRIEF DESCRIPTION OF THE PREFERRED EMBODIMENT

Introduction

In any complex system or process, the states of thousands of discrete devices may be controlled. This system can monitor continuously the state of any aspect of a system or apparatus that can be indicated by the status of a discrete device. For example, the operation of the animation system set forth in the above referenced patent application entitled Digital Animation Apparatus and Methods may be monitored. In the discussion of the preferred embodiment herein, the operation of this monitor system will be made using the animation system as an example only. As will be appreciated, the monitor system may be utilized to monitor any type or kind of system or process. In the animation system, for example, lights may be on or off, curtains opened or closed, figures moved or not, sound tracks switched on or off, and so forth. Similarly, correct operation of many types of devices may be indicated by a discrete output. Examples are outputs of parity check circuits, temperature controllers, water height controllers, and so forth. In each case, the monitor system communicates the status of each discrete event to the central computer if the discrete event is off-normal. The computer then determines whether corrective action should be taken.

Corrective action may take two forms. In the first, the computer may simply output an error message to the system operator via standard output equipment. In the second, the computer may control restoration of the normal condition. In some cases, both responses may occur.

An example in the preferred embodiment of the first response is found in the animation system example in the occurrence of a parity error. A parity check circuit opens a pair of contacts following detection of a parity error. The monitor system communicates this off-normal condition to the computer which outputs a message to the computer operator, informing him of the parity error and its location.

An example of the second response is found in the output of a water height sensor in the animation system example. If the water level falls below a desired point, the level sensor opens a pair of contacts. This off-normal condition is communicated to the computer which, in turn, may control restorative action by turning on a water valve. In addition, the sequence may be reported to the computer operator by an error message.

The monitor system of this invention is essentially a closed loop. It is capable of scanning up to 65,536 contacts (points) in groups of 256 or, in case of an off-normal condition, one set of contacts at a time within a group. It is believed that this is an important feature of this system. It is capable of determining if any point in each 256 point group is off-normal. If so, it can then determine which of the 256 scanned points is off-normal.

In addition, the monitor system of this invention only utilizes the computer when off-normal conditions are encountered. This feature is important since it frees the computer for other work. When an off-normal condition is found by the system, an interrupt to the com-

puter is generated. The computer is programmed to then service the interrupt on a time share basis with other inputs.

GENERALIZED SYSTEM

Referring to FIG. 1, a general block diagram of the monitor system is shown. Via standard input device 945, the computer operator enters a command causing the monitor program to be entered into the core of computer 946. This activates the monitor program and system. Thereafter, the monitoring sequence is initiated under control of the monitor program and continued automatically.

After the monitor program is loaded, computer 946 initializes monitor scanner 947 via control line 948. The monitor scanner then automatically begins and continues the monitoring sequence without computer intervention so long as no off-normal conditions are located. At the end of the scan or when an off-normal point is found, the monitor scanner generates an interrupt to computer 946 via line 949. The interrupt, having been assigned a priority by the computer executive program, causes the computer to process the information delivered to it by the scanner when the priority level is reached.

As will be explained in connection with the explanation of the scanning circuit, "normal condition" are defined herein as closed contacts. So long as the monitor scanner, then, finds all scanned contacts closed, no computer interrupt is generated. "Off-normal" is defined as open contacts. When this condition is found, the monitor scanner so advises the computer and also supplies it with the identity of the open contacts. The computer then checks a catalog of subroutines to determine what action is to be taken in response to the off-normal condition.

As will be readily appreciated, the monitor system of this invention is not limited to the sensing of closed contacts. Closure of normally open contacts may be readily sensed by inclusion of a small relay between the scanned points and the scanning circuit.

Scanned points (contact pairs) are connected to scanning circuits which, in turn, are grouped within discrete scanning unit modules. Each scanning circuit may sense the state of up to 16 scanned points. Up to 16 scanning circuits may be grouped in a single module termed a discrete scanning unit. Each scanning unit, then, may serve up to 256 discrete points. For purposes of addressing, each discrete scanning unit is considered a single unit.

Scanner 947 contains a counter which generates the address of the discrete scanning unit to be interrogated. In response to the initialization pulse on line 948, the scanner counter is set to 001 and the sequential interrogation begins.

Scanner 947 generates an 18 bit word, including two bits, the ninth and eighteenth, of parity. The first eight address bits of the interrogation word always consists of all ones. This initial byte is recognized as a flag by all discrete scanning units. The second eight address bits (bits nine through 17) contain a unique address generated by the scanner counter.

Each interrogation word is supplied to all discrete scanning units (DSU) in parallel. The initial eight bits (all ones) is recognized by all discrete scanning units. The second eight address bits is unique to one discrete scanning unit.

The 18 bit interrogation word is supplied in parallel to monitor scanner transmitter 950 via parallel lines 951. Transmitter 950 consists of a parallel to serial converter and a bi-phase transmitter. The transmitter is identical to the transmitter circuits used throughout this invention.

Transmitter 950 generates a double redundant output, consisting of serial data (address words here), bit sync and word sync lines. The transmitter is controlled to pass out the contents of the parallel to serial converter by control line 952.

The monitor scanner and its transmitters and receivers are preferably located adjacent the computer in a central area. Serial lines 953, then, serially transmit the scanner interrogation words over substantial distances.

There may be in the monitor system of this invention a maximum of 128 remote terminal units (RTU). For a description of a remote terminal unit, reference is made to the above referenced application entitled Digital Animation Apparatus and Methods. Each unit is served by a single input line for impedance matching purposes. In order to maintain the 600 ohm balanced loads where a plurality of remote terminal units are used, line 953 is inputted to buffer expander 955. The expander is explained in detail in connection with the discussion of FIGS. 14, 15 and 16 in the above referenced application. Its function is to accept a single input consisting of data, bit sync and word sync and supply three identical outputs of each. FIG. 1 illustrates expander 955 as having three outputs 957, 958, 959. It is understood that a single line supplies a single remote terminal unit and, therefore, as many expanders are used as necessary.

For simplicity, only output 958 is shown connected to a remote terminal unit. Serial lines 958 supply the interrogation words to the overhead circuits of remote terminal unit 960. As explained in detail in connection with the discussion of FIGS. 17 and 18 in the above referenced patent application, remote terminal unit overhead 960 serves a number of functions. It converts received data to non-return-to-zero form and tests it for parity, word sync and bit sync accuracy. Upon the occurrence of a predetermined number of errors, overhead 960 automatically switches to the opposite input of the two redundant input lines. The monitor system is advised of such a switch via line 961.

Overhead circuit 960 then converts the serial interrogation word input to parallel form. The parallel interrogation word is outputted via lines 963 along with a data strobe signal on line 964.

Accordingly, output circuits 966 and discrete scanning unit overhead circuits 965 are supplied with two interrogation words in parallel form. The most significant half of each such word is comprised of all ones and is recognized by all discrete scanning units. The least significant half of the word is unique to each discrete scanning unit 965.

There are a maximum of 128 remote terminal units (such as 960) and directly connected discrete scanning units (such as 965) according to this invention. Accordingly, the directly connected discrete scanning unit can be uniquely addressed by the least significant seven of the eight address bits (that is, $2^7 = 128$). The eighth, or most significant bit, however, is reserved for use in addressing a discrete scanning unit, such as 968, connected in parallel to directly connected unit 965. The second unit, which may or may not be used, is termed

the piggyback discrete scanning unit. The address for each discrete scanning unit and its piggyback unit is identical except for the eighth, or most significant, bit. The directly connected scanning unit address always has a zero in the most significant position. A piggyback unit, where present, always has a one in that position of its address.

The first interrogation word transmitted by scanner 947 then, consists of two portions. The first half contains eight ones and a parity bit. The second half contains seven zeroes and a one in the least significant bit position, followed by a parity bit. This is recognized by discrete scanning unit 965 as its address.

Scanning unit 965 contains overhead circuits and up to 16 scanning circuits, such as shown in FIG. 4. Each such scanning circuit is connected to 16 discrete scanned points. The normal condition for each such point is in the closed state. A single scanned open point is detected by overhead circuit 965 as an off-normal condition.

Scanning unit 965 generates one of four outputs in response to receipt of its interrogation word. The output is a function of whether or not all scanned points (up to 256) are normal and whether or not a scanning unit piggyback is connected. Each of the four outputs will be described.

In response to each interrogation word, an 18 bit status word is generated and outputted by the addressed scanning unit over lines 970. The first, or most significant, half (eight bits and parity) of the status word always consists of the address of the answering scanning unit. The output addressing scheme is identical to the input addressing scheme.

The second half of the status word (eight bits and parity) has one of four values, dependent upon whether or not all contacts are normal and whether or not a piggyback unit is connected.

If the status word indicates all contacts closed and no piggyback scanning unit, the address counter in monitor scanner 947 is incremented by one count in response to the output generated by unit 965. A new interrogation word is then transmitted via transmitter 950. Following the first interrogation word of the example herein, the next interrogation word would address discrete scanning unit number 002.

In the practical embodiment of this invention, the monitor scanner, once started, interrogates a new discrete scanning unit (256 scanned points) approximately every 500 microseconds. This scanning sequence and rate is continued until an off-normal condition is encountered.

If, in response to the first interrogation word, the status word returned by overhead unit 20 indicated all contacts normal but a connected piggyback scanning unit, the least significant seven bits of the address counter in scanner 947 are held unchanged and the most significant bit (bit 8) changed to a one. Thus, a new address is generated and forms the second half of a new interrogation word transmitted via transmitter 950. The address of each piggyback unit then, is identical to that of its associated directly connected unit, except for the value of the most significant bit.

The second interrogation word is again applied to all discrete scanning units. It is recognized and responded to, however, only by piggyback unit 968.

Unit 968 replies with a status word consisting, as above, of two parts. The first half contains the address

of the piggyback unit. The second half contains one of two messages, depending upon whether all scanned points were normal or at least one was off-normal. Only one of two messages rather than one of four is sent because there can be no further piggyback units. If the reply indicates all scanned points normal, the scanner counter increments its least significant seven bits by one count and changes the most significant (eight) bit to a zero. Thereafter, the next successive interrogation word is transmitted.

In response to each interrogation word, the addressed discrete scanning unit scans all of its scanned points in parallel. The resultant status word indicates only whether all points are normal or whether any one or more are off-normal.

If the initial parallel scan indicates that any scanned points are off-normal, a second scan routine is automatically initiated by the addressed scanning unit. One at a time, the 16 scanned points of each of the up to 16 scanning circuits are checked. At the end of each circuit scan, the unit generates an eighteen bit word. The first eight bits correspond to the status of the first eight scanned points. Bits 10 through 17 correspond to the status of the second eight scanned points. In each case, a one at any bit position indicates that the correspondingly numbered scanned point is off-normal. As before, bits 9 and 18 are parity bits.

Accordingly, any interrogated discrete scanning unit having one or more off-normal scanned points generates a seventeen word reply. The first word, the status word, contains the unit address and the status of the unit, that is, whether all points are normal or whether any are off-normal, and whether there is a piggyback unit. Following are 16 words, each data bit of which corresponds to the status of one of the up to 256 scanned points.

The 17 words are received serially by scanner receiver 972, converted to parallel form and supplied to scanner 947.

Logic circuitry in scanner 947 first compares the status word address to the address in the interrogation address counter to insure that the proper scanning unit is responding.

Upon decoding the second half of the status word, logic circuitry within monitor scanner 947 recognizes whether an off-normal condition was found and, thereby whether 16 further words will be following. If an off-normal condition was found, monitor scanner 947 immediately signals the computer via line 949. Thereafter, the 17 words are transferred into the core of computer 946 via parallel lines 975. Upon completion of the seventeen word transfer, monitor scanner 947 generates a computer interrupt via line 949. Thereafter, the monitor information is processed by computer 946 in the order dictated by its assigned priority.

Computer 946 is programmed to examine the sixteen words relating to scanned point status bit-by-bit. As a bit denoting off-normal status is located, the computer is controlled by software to refer to a previously stored table of error subroutines. The subroutine may direct the printout of an appropriate error message via output device 945. Or, the subroutine may control restorative action to be taken.

If the subroutine controls the latter, the proper eighteen bit words are read out of memory of computer 946 via parallel lines 977. The word format is identical to that described in connection with the show control

unit. The first half of each word contains an address (other than all ones) and the second half contains restorative data.

Restorative data is transmitted by transmitter 950 in the normal manner. Remote terminal unit 960 receives the data and, as explained above, outputs it in parallel form over line 963. As explained in connection with the control of an animated show (FIGS. 19 and 20), in the above referenced patent application, output circuits 966 take the form of discrete devices. In either case, data transferred from computer 946 may control the devices via output circuits 966 to correct the off-normal condition.

Referring to FIG. 1, discrete scanning unit 965 is shown with a single output line 970. Within unit 965 is a bi-phase transmitter circuit which forms the double redundant data, bit sync and word sync outputs used throughout this invention for transmission of data over distances. In FIG. 1, this bi-phase transmitter output is represented by line 970. Data is, as with all bi-phase transmitters, outputted serially by bit.

As explained elsewhere, data is transferred herein over 600 ohm balanced lines. Where more than one input is involved, therefore, the inputs must be multiplexed through a buffer concentrator. Since the monitor system of this invention may comprise up to 128 directly connected discrete scanning units, each with its own output, a plurality of buffer concentrators may be necessary. Each combines and multiplexes three inputs to a single output.

Buffer concentrator 980 accepts three input lines 970, 981, 982 and outputs a single parallel line 983. Details of the buffer concentrator may be found in the specification in connection with the discussion of FIGS. 9 and 10 in the above referenced patent application.

Scanner receiver 972 includes the identical bi-phase receiver circuit shown in FIG. 17 in the above referenced patent application. It converts the received bi-phase data to non-return-to-zero coding and applies the data coding to a serial-to-parallel converter. The output of the converter is transferred to monitor scanner 947 over parallel lines 984. When the converter is fully loaded and ready to transfer, line 986 is turned on, controlling acceptance of the transferred word.

Following each processing of off-normal data, the computer controls, via line 948, the monitor scanner to begin its scanning sequence. In each case, the scanner retruns to its last scanned discrete unit address, increments the interrogation counter by one count, and continues from that point. After the last (highest address) discrete scanning unit is interrogated, the sequence begins as before with the first (lowest address) scanning unit.

As will be explained in connection with the discussion of FIG. 2, the scanner may be controlled, via a radix control, to scan only up to a certain address before repeating. Further, via software control, the computer keeps a record of each reported off-normal condition and only executes the error subroutines in the case of changes. In this way, an error message is only outputted once in response to an off-normal condition.

The monitor system of this invention, then, provides the ability to check the status of up to 65,536 discrete points. In groups of up to 256, the points are scanned sequentially in parallel. If an off-normal condition is located in any one group, each point in that group is sequentially scanned and the status communicated to a

computer. Computer time is only utilized when off-normal conditions are located and during control periods.

MONITOR SCANNER

In connection with the above discussion of FIG. 1, the operation of monitor scanner 947 was disclosed in connection with the monitor system. Referring to FIG. 2, a detailed diagram of the monitor scanner is illustrated along with details of the scanner receiver and scanner transmitter.

As described above, when the computer operator calls up the monitor program, the monitor circuit is initialized via computer control line 948. Control logic 990, via control line 991, causes discrete scanning unit address generator 992 to reset to the initial scanning unit address, or 001. Generator 992, consisting of a controllable counter, outputs the scanning unit address over parallel lines 993 to one input of parallel to serial converter 995.

It will be recalled that interrogation words are 18 bits in length and consist of two halves. The most significant half contains eight ones which serve as a flag recognized by all discrete scanning units. The second half contains eight bits indicating the interrogated scanning unit address. Each half is followed by a single parity bit.

The flag address half is inputted to converter 995 via parallel lines 996. The first half of each interrogation word, then, is obtained by converter 995 from input lines 993. The second half, or scanning unit address, is obtained by the converter from input line 996.

Converter 995 is a side loading counter. It is cycled out serially by control of logic 990 via control line 997. Its serial output is supplied to bi-phase transmitter 998 via line 999.

Transmitter 998 is disclosed in detail in FIG. 25 in the above referenced patent application. For the description here, it is sufficient to understand that it provides double redundant outputs of interrogation data, bit sync and word sync over serial lines 953.

As described in connection with FIG. 1, data transmitted over line 953 is supplied in parallel to all directly connected scanning units and output circuits. Depending upon the status of the scanned points connected to each of the units, each interrogated unit returns either a single 18 bit status word or the status word and 16 words each 18 bits in length. After passing through one or more buffer concentrators, the scanning unit return is received serially by bi-phase receiver 1000, over serial lines 983.

Receiver 1000 is identical to the receivers utilized throughout this invention and is disclosed in detail in FIG. 17 in the above referenced patent application. Its function is to accept the bi-phase encoded data, bit sync and word sync codes and output the data in non-return-to-zero form on line 1001.

Serial to parallel converter 1002 receives the serial data on line 1001 and end loads a series of shift registers. When converter 1002 is filled, the eighteen bits of the status word are available to buffer register 1004 via parallel lines 1005, available to the three stage detector unit 1006 via lines 1007 and to address comparator 1008 via lines 1009.

Address comparator 1008 is provided with two inputs, the returned scanning unit address from lines 1009 and the transmitted scanning unit address from lines 1010. Its function is to insure that the addressed

scanning unit was the unit that responded. If comparator 1008 finds that the addresses match, it turns on line 1011, so advising control logic 990. Via control lines 1012 and 1013 logic 990 causes detector unit 1006 to diagnose the received status word.

Detector unit 1006 consists of three stages 1014, 1015, 1016, each for checking the status of aspects of the received status word.

Status detector 1014 serves a number of functions. It determines whether two or more scanning units tried to transmit at one time, whether the entire scan has been received, that is, whether one of 17 words have been received, whether a parity error occurred, and whether no response was received within a predetermined time limit. To indicate each of these conditions, a number of control lines are connected to logic 990. For simplicity, these lines are represented by line 1018.

Status detector 1015 checks the last half of the received status word to determine whether all scanned points were found to be normal or whether any were off normal. If all were normal, logic 990 is advised by line 1019 and, in turn, controls generator 992 via line 991 to generate a new interrogation address in accordance with the second address control via line 1020, as will be discussed.

If any off-normal scanned points were located, logic 990 indicates this to the computer via line 949. In such a case, 16 additional words are in the process of being transmitted via input line 983. In addition to signaling the computer, logic 990 also cycles buffer register 1004 via line 1022 to accept and pass the status word, and all 16 words following, to the computer via input lines 975.

In the event of off-normal conditions, control logic 990 generates a second status word containing the results of the testing by detector units 1006. This new status word is passed to the computer via parallel lines 1025 and 975.

Detector 1016 checks the last half of the status word to determine whether a piggyback unit is connected to the transmitting scanning units. If so, line 1020 is turned on to set a flip-flop in generator 992 to supply a binary one in the most significant bit position for the next scan.

The received words continue to be passed to the computer input register via buffer register 1004 until detector 1014 determines that the transmission has ended. Line 1022 thereafter ceases to cycle register 1004. If all points were found to be normal, address generator 992 transmits a new interrogation word and the above sequence is repeated. If points were found to be off-normal, the monitor scanner waits until it is controlled to resume scanning by computer control line 948.

In response to an off-normal scan, the computer, as previously explained may output restorative data via lines 977. This data, as in the case of the show control unit, would consist of 18 bit words. The first half would contain the address of the restoring output circuit and the second half would contain the restoring data.

Restorative information is passed via the computer output to buffer register 1028. When full, the contents of register 1028 are emptied via line 1029 to parallel to serial converter 995. Thereafter, the restorative information is transmitted to the proper output circuits (966, FIG. 1).

Upon the completion of the error processing sequence by the computer, logic 990 is controlled via line 948 to begin the scanning process anew. Generator 992 is then controlled via line 991 to generate the next address and scan the next scanning unit.

Radix control 1030 is provided with two inputs. One is the address provided by address generator 992 via lines 1031 and the second is the manually entered maximum address. The latter is entered via binary switches 10 (not shown). Radix control compares the two inputs and resets generator 992 via line 1033 when the inputs are equal. In this way, the scanning range of the monitor system may be determined.

DISCRETE SCANNING UNIT OVERHEAD

Each discrete scanning unit (DSU), whether directly connected to a remote terminal unit or converted as a piggyback unit, is assigned a unique address. When properly addressed, each unit can scan the status of up to 256 contacts. Closed contacts are considered to be in a normal condition. If all contacts are closed, the unit is in its normal condition. If one or more of the contacts are open, an off-normal condition exists. It is the function of the discrete scanning unit to advise the monitor scanner, when interrogated, whether all contacts are normal and, if not, which contacts are off-normal.

Each discrete scanning unit contains up to 16 scanning circuits, which will be described in the following section. Each scanning circuit, in turn, is connected to up to 16 scanned points or pairs of contacts.

In addition to the scanning circuits, each unit contains circuitry for decoding received interrogation words, controlling the scans and generation of reply codes. These functions are performed in the overhead circuits of each scanning unit.

Referring to FIG. 3, a block diagram of the overhead circuit of a discrete scanning unit is illustrated. Eighteen bit interrogation words are received by each discrete scanning unit overhead over parallel lines 1040. Flag and address detector 1041 checks each received interrogation word for the address byte common to all discrete scanning units (all one's) and the address byte unique to that unit. The common flag byte is used because of the presence of the output circuits (966, FIG. 1) which also receive the interrogation words and restorative data words. Since the initial portion of a restorative data word contains an address byte, this same format must be followed for the discrete scanning units.

It will be recalled that a two part status word is always returned from an interrogated discrete scanning unit. The first half consists of the address of the replying unit and the second half is set by four conditions; whether or not a piggyback unit is connected and whether or not all scanned points are normal.

Referring again to FIG. 3, as soon as flag and address detector 1041 recognizes the received interrogation word as its address, the second half of the interrogation word (the d.s.u. address) is made available to status scanner gates 1042 over parallel lines 1043. Line 1044 is controlled to be on by detector 1041 if a piggyback unit is connected. The presence or absence of a piggyback unit is indicated by a wired pin within detector 1041.

Parallel lines 1043, then contain the information necessary for the first half of the status word to be returned.

Detector 1041 also turns on or holds off line 1045 depending upon whether the received interrogation word contained an address of a directly connected or piggy-back unit. This is determined by whether the most significant bit is a one or zero. It will be recalled that the seven least significant bits in the addresses of both units are identical. The difference is found in the most significant (eight) bit. In a piggyback unit, that bit is a one.

Line 1045 is connected to bit sensor 1047 to control whether sensor 1047 accepts serial input 1049 or 1050. The purpose of this control will be discussed below. Line 1045 also supplies the same information to status scanner gates 1042, that is, whether a directly connected or piggyback unit was addressed.

As will be explained below, prior to reception of the interrogation word, bit sensor 1047 was supplied with the information as to whether or not all contacts were normal or if any were off-normal. In response to this, the state of line 1051 is controlled. If, then, prior to receipt of the interrogation words, all scanned points were normal, line 1051 is off; if any scanned points were off-normal, line 1051 is on.

Accordingly, status scanner gates 1042 is supplied with all the information necessary for the status word to be returned as soon as the interrogation word is received by the overhead circuitry. The initial half, the unit address, is contained on parallel lines 1043. Information for the second half is found on control lines 1044, 1045 and 1051.

Returning to the point in time when flag and address detector recognizes its address, it then turns on line 1053. This controls the overhead to set a flip-flop in status scan control 1054 and start the scanning count which will cause return of the status word.

When the flip-flop in status scan control 1054 is set, lines 1055 and 1056 are turned on. As will be explained below, when line 1055 is turned on, the "all points" scanning lines are turned off and a scanning count begins on lines 1058. When line 1056 turns on, status scanner gates 1042 uses the scanning count pulses on parallel lines 1058 to scan parallel lines 1043 for the first half of the status word and scan logic gates set by the information inputs to gates 1042 for the second half.

The scanned status word is outputted serially on line 1060 to return-to-zero (RZ) to non-return-to-zero (NRZ) converter 1061. Converter 1061 is used to convert the scan status word to the code format used throughout the invention.

Thereafter, the status word is supplied to bi-phase transmitter 1063 via line 1064 and returned to the monitor scanner receiver (947, FIG. 1) via line 1065.

The above sequence for the status word return is performed in response to every decoded interrogation word, whether or not all points were normal. If all were normal, no further transmission is made.

Before explaining operation of the circuit in the event of points being found off-normal, a description of the constant monitoring feature will be given.

It will be recalled that the status of up to 256 scanned points is monitored by a single unit. As will be explained in connection with FIG. 4, each point, or all points may be selected by proper pulsing or matrix lines. When all matrix lines are on, the outputs of all scanning circuits are paralleled. The paralleled output has a state determined by whether all points are normal or if one, or more, are off-normal. This will be ex-

plained in greater detail in connection with the discussion of that FIGURE.

The matrix scanning lines are connected to each of the up to sixteen scanning circuits from scanner gates 1068 and piggyback scanner gates 1069 (if used). In each the status of the matrix lines is controlled by scan bit counter 1070 via lines 1071, 1072.

When the scanning unit is quiescent, that is, when it has not been interrogated, line 1055 is off and all matrix scanning lines ("all lines") are on. This causes the status of the scanned points to control the state of scanning circuit output lines 1049, 1050. For example, if all scanned points scanned by gates 1068 are normal during a quiescent period, line 1049 is up; if any are off-normal, the line is down.

Logic in bit sensor 1047 is set dependent upon the state of scanning circuit output lines 1049, 1050. When flag and address detector 1041 decodes an interrogation word, line 1045 is turned on, locking the status of the scanning circuit input lines in bit sensor 1047. Thereafter, the status of the lines is made available for the status word on line 1051, as explained above.

If bit sensor 1047 was controlled from a normal set of scanning circuits, line 1075 is held off. If, however, any points are found off-normal, line 1075 is turned on. As will be explained this is used to help control a point scan.

After scan bit counter 1070 completes the scan for the status word, it turns on line 1071 to status scan control 1072. The latter then turns on line 1073.

If lines 1075 and 1073 are both on, bit sensor 1047 had sensed an off-normal condition. The two lines then control data scan control 1077 to turn on line 1078. Line 1078 serves two purposes; it starts the scanned point scan by scan bit counter 1070 and controls converter 1061 to accept inputs from line 1079 rather than 1060.

When line 1078 turns on, scan bit counter 1070 begins to sequentially pulse scanning circuit matrix lines 1071, 1072. As will be explained below, sequential scanning causes a serial read-out of status bits from the scanning circuits via output lines 1049 or 1050.

Bit sensor 1047 accepts whichever scanning circuit input it had been previously controlled by line 1045 to accept and passes the status bits to converter 1061 and parity generator 1080 via line 1079. Generator 1080, via line 1082, adds the proper odd-parity bits to the bit stream. The sixteen eighteen bit words are then returned to the monitor receiver via line 1065.

Clock generator 1085, connected to scan bit counter 1070 via line 1087, to converter 1061 via line 1088 and bi-phase transmitter 1063 via line 1089, supplies the proper scan rates and bit transmission rates.

DISCRETE SCANNING CIRCUITS

Each overhead circuit controls the scanning of up to 16 scanning circuits with 16 scanned points on each circuit. The schematic diagram of a single scanning circuit is illustrated in FIG. 4. Since the operation of the circuit is readily apparent to a person skilled in the art, only a brief description will be given.

A scanning circuit consists of eight substantially identical sections. FIG. 4 shows three 1090, 1091, 1092 of the eight sections. Each section is connected to a pair of contacts. For example, section 1090 contains contact pairs 1093, 1094, section 1092, 1095, 1096, and so forth.

Each section is divided into upper and lower, identical, halves. Each half contains one set of scanned points or contact pairs. Each half is comprised of a five-input AND gate. Four of the five are scanning inputs and the fifth is the scanned point input. The AND gate is of familiar design.

All of the halves are outputted onto common line 1097 from half lines 1098, 1099. Output line 1097 forms the input to the bit sensor (line 1049 or 1050, FIG. 27 in the above referenced patent application).

There are two levels of scan lines. The major level consists of four lines **1100**, **1101**, **1102**, **1103** and the minor level consists of eight lines of which three **1105**, **1106**, **1107** are shown.

During quiescent periods, all scanning lines are up. If one scanned point is off-normal, line **1097** is up. For example, if contacts **1093** are open, a raised level is caused on line **1110** and, therefore, on line **1097**. Any open contact, then causes line **1097** to be up.

Major lines are scanned to select halves of scanning

circuits. Scanning line 1103 selects half of the discrete scanning unit. Line 1100 selects one scanning circuit within the half. Lines 1101, 1102 select the upper or lower halves of the cards.

5 If, then, line 1105 is pulsed after the upper half of all cards have been selected, contacts 1093 are monitored. By containing such a scan, the status of each of the 16 scanned points is outputted over line 1097.

MONITOR SYSTEM SOFTWARE

As described above, the monitor system according to this invention utilizes a programmed general purpose digital computer. The computer utilized by applicants in this invention is a Honeywell DDP-516, manufactured by Honeywell, Inc. Accordingly, the Monitor System program is written in a language suitable for that computer. The program set forth herein is in a basic assembly language, termed DAP-16 by Honeywell. This is a Honeywell language utilized for all of their 16 bit computers. The monitor system program is as follows.

We claim:

1. In a system for monitoring the status of discrete devices and transmitting status information to an external computer, the combination comprising:
  - a. a group of said discrete devices, each of said discrete devices being in (1) a normal state, or (2) an off-normal state;
  - b. means for generating an interrogation signal for initiating a determination of said states of said devices;
  - c. scanning means coupled to said generating means to receive said interrogation signal, said scanning means for scanning said states of all of said discrete devices in said group simultaneously, said scanning means including means for generating a first response signal dependent on said states of said discrete devices in said group;
  - d. means responsive to said first response signal for scanning each of said discrete devices individually

50

- when at least one of said devices in said group is in said off-normal state; and
  - e. means responsive to said individual scanning means for generating a second response signal to said computer in accordance with said state of each of said devices in said group only when at least one of said devices in said group is in said off-normal state, said computer for outputting predetermined signals to said discrete devices for control thereof responsive to said second response signal generation.
2. The system of claim 1, wherein said interrogation signal generation means comprises counter means for generating an address signal unique to said group of discrete devices.
  3. The system of claim 2, wherein said interrogation signal generation means further comprises means for altering the contents of said counter means.

4. The system of claim 3, wherein said altering means comprises means for incrementing the count in said counter means by one count following each complete scan by said scanning means.

5. The system of claim 2, further comprising means for comparing the generated address signal with a portion of the first response signal.

6. The system of claim 5 wherein said comparing means comprises status detection means, said comparing means having means for enabling said status detection means subsequent to the occurrence of a predetermined comparison between said generated address signal and said portion of said first response signal.

7. The system of claim 1, wherein said scanning means comprises address detector means for generating a signal identifying a particular scanning means having said first response signal transmitted thereto.

8. The system of claim 7, wherein said scanning means comprises:

- a. bit sensor means for generating a signal in accordance with whether any of said devices are in said off-normal state or whether all of said devices are in said normal state; and,
- b. status scanning means for forming said first response signal from said signal from said address detector means and said signal from said bit sensor means.

9. The system of claim 8, wherein said scanning means further comprises second counter means for generating pulses for scanning the state of each of said devices.

10. The system of claim 1, further comprising:

- a. at least one additional group of said discrete devices;
- b. first counter means for generating an address signal unique to at least one of said groups of said discrete devices;
- c. means for altering the contents of said counter means subsequent to a scan by said simultaneous scanning means, said scanning means further including,
- d. scanner gating means for generating a signal in accordance with the address of said scanning means;
- e. bit sensor means for generating a signal in accordance with whether any of said devices are in said off-normal state or whether all of said devices are in said normal state; and,

15 f. status scanning means for forming said first response signal from said signal from said scanner gating means and said signal from said bit sensor means.

5 11. The system of claim 10, wherein said scanning means further comprises second counter means for generating pulses for scanning the state of each of said devices.

10 12. In a system for monitoring the status of discrete devices and transmitting status information to an external computer, the combination comprising:

- a. a plurality of groups of discrete devices, each of said groups comprised of a plurality of said devices, each of said discrete devices being in (1) a normal state, or (2) an off-normal state;
- b. counter means for generating an interrogation signal for initiating a determination of said states of said devices in one of said groups;
- c. means for altering the count in said counter means following each group state determination, said altering means including sensor means connected to receive said interrogation signal for developing a first response signal indicating whether all of said devices in a group are in said normal state or if any of said devices in said group are in said off-normal state;
- d. scan control means connected to receive said control signal for sequentially scanning the status of each of said discrete devices in a group when said first response signal indicates that at least one of said devices is in said off-normal state and for developing a second response signal in accordance with said state of each of said devices in said group, said second response signal being transmitted to said external computer, said computer for outputting predetermined signals to said discrete devices for control thereof responsive to said second response signal; and
- e. sequencing means responsive to said interrogation signal from said counter means for operating on a further group of discrete devices.

13. The system of claim 12, further comprising means for passing said second response signal to said computer under control of said first response signal.
